United States Patent Office

Des. 182,998
Patented June 10, 1958

182,998

MOTOR COACH

Roland E. Gegoux and William P. Strong, Pontiac, Mich.,
assignors to General Motors Corporation, Detroit,
Mich., a corporation of Delaware

Application December 4, 1957, Serial No. 48,769

Term of patent 7 years

(Cl. D14—3)

The essential features of our design reside in the portions shown in full lines.

We claim:

The ornamental design for a motor coach, substantially as shown and described.
